UNITED STATES PATENT OFFICE.

LA QUINNO RHOADES, OF FREMONT, OHIO.

PRINTING PRESS.

1,409,240.

Specification of Letters Patent. Patented Mar. 14, 1922.

Application filed June 22, 1921. Serial No. 479,694.

To all whom it may concern:

Be it known that I, LA QUINNO RHOADES, a citizen of the United States, and a resident of Fremont, in the county of Sandusky 5 and State of Ohio, have invented certain new and useful Improvements in Printing Presses, of which the following is a specification.

The present invention relates in general 10 to inking mechanism for printing presses, and more particularly to an improved track and adjusting mechanism therefor especially adapted for use with printing presses of the platen type.

In certain types of printing presses, notably the Gordon type, inking rollers travel 15 back and forth over the inking table or disk and the type form or bed at every cycle of the press thereby taking the ink from the inking table and transferring or applying it upon the type in the form. Such inking rollers are usually provided with rolls or trucks which run upon tracks. The inking rollers vary somewhat in diameter due to 20 physical changes in the environment and due to wear and again a small form does not require as much pressure of the inking roller upon the face of the type to properly apply the ink as does a larger form. Consequently 25 considerable difficulty has been experienced in having the roller properly apply or transfer the ink when the size of the inking rollers vary or when widely different forms are used.

One of the principal objects of the present invention is to provide improved tracks 30 for the trucks or rolls of the inking rollers which are readily adjustable to compensate for wear or to adapt the inking mechanism 35 to various sizes of forms and thereby overcome the difficulties heretofore encountered.

Another object is to provide an improved track which has capacity for all necessary adjustment and which affords a positive 40 bearing for the trucks of the inking rollers in all positions thereof.

Another object is to provide an improved track of this character which is of simple 45 and durable construction, reliable in operation and easy and inexpensive to manufacture and which may be readily and accurately adjusted by a simple manipulation of its controlling elements.

Other objects and advantages of the invention reside in certain novel features of 50 construction, combination and arrangement

of parts which will be hereinafter more fully described and particularly pointed out in the appended claims, reference being had to the accompanying drawings forming part of 60 this specification, and in which:

Figure 1 is a side elevational view illustrating the track and its adjusting mechanism for showing a portion of the frame of 65 the press;

Figure 2 is a detail perspective view of the movable web of the adjusting mechanism;

Figure 3 is a detail perspective view of the supporting plate of the hanger; and

Figure 4 is a similar view of the foot plate 70 of the support of the upper arm of the track.

Referring to the drawings wherein for the sake of illustration is shown the preferred embodiment of the invention the numeral 75 10 designates the frame of the press which is preferably of the bed-and-platen of Gordon type. The frame may be of any conventional construction and supports the usual inking table or disk (not shown) and 80 the usual bed or form (not shown). Inking rollers designated at 11, are provided and as usual travel back and forth over the inking disk and table and the type at every cycle of the press thereby taking the ink 85 from the inking table and transferring or applying it upon the type. These inking rollers are provided with trucks or rolls 12 which ride upon a track, designated generally at 15. This track comprises a vertical arm or portion 16, a lower curved arm or portion 17, and an upper arm 18 which extends adjacent the inking table.

The upper arm 18 of the track has a depending lug 19 provided with a threaded 90 bearing 20. An adjusting screw 21 has one end cooperatively engaged with the threaded bearing 20 and is itself adjustably supported on a foot plate 22 secured upon the end 23 of the fountain stand and a shoulder 24 100 provided adjacent the upper corner of the frame. The adjusting screw 21 is adjustably mounted in an elongated slot 25 provided in the foot plate 22 by means of its head 26 and lock nuts 27. The head engaging one side of the foot plate and the lock nuts operating against the opposite side thereof whereby the screw is secured in any position in which it may be adjusted along the foot plate. Adjusting mechanism is 110 provided for the vertical arm of the track and includes a stationary wedge member 30

formed upon the main frame including inclined surfaces 31 and 32 and a movable wedge member 35 interposed between the frame and the vertical arm of the track 5 and including inclined surfaces 36 and 37 cooperatively engaged with the inclined surfaces 31 and 32 of the stationary wedge member. Both the stationary wedge member and the movable wedge member are combined, as shown in the drawings, and it is obvious that as the movable wedge member is adjusted along the stationary wedge member the track will be adjusted toward and away from the frame and consequently 10 toward and away from the bed or form.

A hanger, designated generally at 40 carries the movable wedge member 35 and it includes a hanger plate 41 secured by means of a bolt 42 to the upper corner of the 20 frame 10. The projecting portion of the hanger plate is provided with an elongated slot 43 and a hanger bolt 44 extends through the slot and is adjustably secured therein by means of its head and a lock nut 45, the 25 head engaging one side of the hanger plate and the lock lug engaging the other side thereof. The shank of the hanger bolt is threaded, as indicated at 46 and is operatively engaged with the upper end of the 30 movable wedge member, the movable wedge member having an internally threaded opening at its upper end and operatively engaged with the threaded shank of the hanger bolt in order that the hanger bolt may 35 be turned, when the lock nut 45 is released to adjust the movable wedge member along the stationary wedge member.

Gripping bolts, designated at 50 and 51 are provided and have one end connected 40 with the vertical arm of the track and extend through elongated openings 52 and 53 provided in the movable wedge member and through similar openings 54 and 55 provided in the portion of the frame which 45 constitutes the stationary wedge member, the free ends of the bolts being threaded and being engaged with lock nuts 58 and 59. It is obvious that the spaces defined by the 50 openings 56 and 57 afford an easy access to the lock nuts 58 and 59 and permit of the use of a wrench or other suitable instrument. It is also apparent that the elongated openings 52 and 53, and 54 and 55 permit of the 55 necessary movements of the bolts incident to adjustment of the track.

A tension screw 60 has its threaded shank adjustably engaging in the threaded opening provided in the lower end of the arm 17 of the track and its head is adapted to 60 abut the adjacent portion of the frame of the press.

In operation, when it is necessary to make an adjustment of the track, lock nuts 58 and 59 are loosened and the lock nuts 27 are 65 also loosened. The lock nut 45 is then run

down on the threaded shank of the hanger bolt and the hanger bolt is turned to raise or lower the movable wedge member thus permitting the track to move toward the frame or force it to move away therefrom 70 as desired. When the track has been adjusted by means of the hanger bolt to the desired position, the lock nuts 58 and 59 of the gripper bolts are tightened and the lock nuts 27 are also tightened and this locks 75 the track in position. The adjustment is thus effected by manipulation of a single bolt, that is the hanger bolt. The other bolts act to tighten and more positively support the track in position after the adjustment has been made.

In this manner the tracks may be adjusted to compensate for the wear of the inking roller and for variations in its size, due to other conditions and also may be adjusted 80 in order to obtain the proper pressure of the roller upon the face of the type when the forms vary in character or in size.

I claim:

1. In a printing press, a frame, a track 90 for the trucks of the inking rollers including a vertical arm and an upper arm, a depending lug carried by the upper arm and having a threaded bearing therein, an adjusting screw cooperatively engaged with the 95 threaded bearing, a foot plate mounted upon the frame having an elongated slot receiving said adjusting screw, lock nuts for securing the adjusting screw in position on said foot plate, a stationary wedge member 100 formed on the frame and having a pair of inclined surfaces, a movable wedge member interposed between the vertical arm of the track and the frame and having a pair of inclined surfaces cooperatively engaged with 105 the stationary wedge member, a hanger carrying said movable wedge member and including a hanger plate carried by the frame and having a projecting portion provided with an elongated slot, a hanger bolt adjustably secured in said slot and having threaded engagement with said movable wedge member, and gripping bolts carried by the track and secured to said frame. 110

2. In a printing press, a frame, a track 115 for the trucks of the inking rollers and including a vertical arm and an upper arm, means for adjusting the upper arm of the track, a stationary wedge member formed on the frame and having a pair of inclined 120 surfaces, a movable wedge member interposed between the vertical arm of the track and the stationary wedge member and having a pair of inclined surfaces cooperatively engaged with the stationary wedge member, a hanger carrying said movable wedge member and including a hanger plate carried by the frame and having a projecting portion provided with an elongated slot, and a hanger bolt adjustably secured in said slot 125 130

and having threaded engagement with said movable wedge member, and gripping bolts carried by the track and secured to said frame.

5. 3. In a printing press, a frame, a track for the trucks of the inking rollers and including a vertical arm and an upper arm, means for adjusting the upper arm of the track, a stationary wedge member formed 10 on the frame and having a pair of inclined surfaces, a movable wedge member interposed between the vertical arm of the track and the stationary wedge member and having a pair of inclined surfaces cooperatively engaged with the stationary wedge member, a hanger carrying said movable wedge member and including a hanger plate carried by the frame and having a projecting portion provided with an elongated slot, and a 15 hanger bolt adjustably secured in said slot and having threaded engagement with said movable wedge member.

4. In a printing press, a frame, a track for the trucks of the inking rollers including 20 a vertical arm and an upper arm, a depending lug carried by the upper arm and having a threaded bearing therein, an adjusting screw cooperatively engaged with the threaded bearing, a foot plate mounted 25 upon the frame having an elongated slot receiving said adjusting screw, lock nuts for securing the adjusting screw in position on said foot plate, and adjusting mechanism for the vertical arm of the track.

5. In a printing press, a frame, a track for the trucks of the inking rollers including 30 a vertical arm and an upper arm, means for adjusting the upper arm and adjusting mechanism for the vertical arm including a stationary wedge member on the frame, a movable wedge member interposed between the track and the frame and cooperating with the stationary wedge member, means for adjusting said movable wedge member 35 and gripping bolts cooperating with the frame, track and movable wedge member.

6. In a printing press, a frame, a track for the trucks of the inking rollers including 40 a vertical arm and an upper arm, means for adjusting the upper arm including a foot plate and an adjusting screw, adjusting mechanism for the vertical arm of the track including a stationary wedge member, a movable wedge member cooperating 45 with the stationary wedge member, a hanger carrying said movable wedge member, and

gripping bolts cooperating with said vertical arm, said movable wedge member and said frame.

7. In a printing press, a frame, a track 50 for the trucks of the inking rollers including a vertical arm and an upper arm, means for adjusting the upper arm including a foot plate and an adjusting screw, adjusting mechanism for the vertical arm of the track 55 including a stationary wedge member, a movable wedge member cooperating with the stationary wedge member, and a hanger carrying said movable wedge member.

8. In a printing press, a frame, a track 60 for the trucks of the inking rollers including a vertical arm and an upper arm, a lug carried by the upper arm and having a threaded bearing therein, an adjusting screw cooperatively engaged with the threaded 65 bearing, a foot plate arranged upon the frame, means for securing said adjusting screw in position on said foot plate, adjusting mechanism for the vertical arm of the track including a stationary wedge member 70 formed on the frame, a movable wedge member interposed between the track and the frame and coacting with the stationary wedge member, a hanger carrying the movable wedge member and including a hanger 75 plate carried by the frame, a hanger bolt adjustably carried by the hanger plate and having threaded engagement with the movable wedge member, and gripping bolts carried by the track and cooperating with the 80 wedge member and with the frame.

9. In a printing press, a frame, a track for the trucks of the inking rollers including 85 a vertical arm and an upper arm, a lug carried by the upper arm and having a threaded bearing therein, an adjusting screw cooperatively engaged with the threaded bearing, a foot plate arranged upon the frame, means for securing said adjusting screw in position on said foot plate, adjusting mechanism for the vertical arm of the track including a stationary wedge member 90 formed on the frame, a movable wedge member interposed between the track and the frame and coacting with the stationary 95 wedge member, a hanger carrying the movable wedge member and including a hanger plate carried by the frame, and a hanger bolt adjustably carried by the hanger plate and having threaded engagement with the 100 movable wedge member.

LA QUINNO RHOADES.
